CLAIM

The ornamental design for a curling iron holder, as shown and described.

DESCRIPTION

FIG. 1 is a top perspective view of a curling iron holder embodying my design;

FIG. 2 is a top plan view of the curling iron holder as seen in FIG. 1, the bottom being planar and unornamented;

FIG. 3 is a side elevational view thereof; and,

FIG. 4 is a cross-sectional view as seen along lines 4—4 of FIG. 3.
